By his atty.

UNITED STATES PATENT OFFICE.

HENRY S. HALE, OF PHILADELPHIA, PENNSYLVANIA.

CAR-SEAT.

SPECIFICATION forming part of Letters Patent No. 359,354, dated March 15, 1887.

Application filed August 26, 1886. Serial No. 211,893. (No model.)

To all whom it may concern:

Be it known that I, HENRY S. HALE, of the city and county of Philadelphia, and State of Pennsylvania, have invented an Improvement 5 in Car-Seats, of which the following is a specification.

My invention has reference to car-seats; and it consists in certain improvements, fully set forth in the following specification, and shown 10 in the accompanying drawings, which form part thereof.

This invention is for the same object as that set out in my application filed April 14, 1886, and serially numbered 198,800—viz., to form a 15 car-seat in which the seat proper shall be capable of tipping and shall be moved automatically toward the front and tipped or tilted by the act of reversing the back.

My object is, also, to so construct the seat 20 that it shall be capable of being turned in so short a distance that I am enabled to use extremely high seat-backs, or those provided with head-rests, and yet turn them in the limited space allowed upon the railway-cars.

My object is, also, to hinge the back to its 25 arms, so that when in its extreme positions it is locked from oscillating upon said arms and shall be incapable of oscillating until raised to a vertical or substantially vertical position 30 over the seat, whereby the seat may be readily raised, the back and arms being practically rigid with respect to each other until the vertical position is assumed. In such position the locks unlatch and the back may be oscillated by hand so as to bring the advancing or 35 forward edge down before completely turning the back into position, thereby causing it, when a very high back is used, to clear the next adjacent seat-back. In the device illustrated in the patent to Cobb, (partly owned 40 by me,) dated May 26, 1885, the seat-back is locked to its arms until fully thrown over, as the gravity-pressure of the back operates the locks, and therefore a head-rest could not be 45 used. In my present device the back is locked to the arms by intermittently-acting pawls or locking devices which unlock the back when the arms stand in a vertical position over the seat.

My object is, also, to pivot the said seat-back 50 arms close to the seat and connect them by means of a rack-and-pinion device with the

seat-carrying frame, whereby the movement of the seat-back will shift the seat in the proper direction with a uniform movement and at the same time hold the seat-frame down and lock 55 it from displacement. The seat-frame runs upon cam-faces, substantially in the manner set out in my former application herein referred to, for the purpose of tipping or tilting 60 the seat in the act of shifting it.

The idea of pivoting the back-supporting arms close to the seat and shifting the seat thereby, broadly, is not new, as somewhat the same principles are embodied in Patent No. 65 281,129; but my improved device, by which this result is accomplished in so perfect a manner, and whereby additional advantages are attained, is new, as far as I am aware, and renders what was heretofore an unsatisfactory 70 and, I may say, impracticable device, now operative with the highest degree of utility and comfort.

In the drawings, Figure 1 is a sectional elevation on line xx of a car-seat embodying my 75 invention. Fig. 2 is a sectional elevation of part of same on line yy . Fig. 3 is a side elevation of the hinged connection between the back and its arm, with the covering-plate removed to show the interior. Fig. 4 is a perspective view of the upper end of the seat-back arms, and Fig. 5 is a section on line zz of Fig. 1.

A is the main frame, and B is the arm thereof. C is a casting secured to the frame A, and 85 is provided with sockets D for the reception of the ends of the longitudinal frames E, of wood. These plates C (one being upon each end of the seat) are provided with oblique cam-faces d , the incline pointing in opposite directions for the purpose of guiding the seat-carrying frame.

The seat-carrying frame consists of two end metal plates, F, connected by wooden ties G, upon which ties the seat proper, H, rests. The 95 end plates, F, are provided on their lower parts with the projections f , which work upon the cam-face d , and at such a distance apart that when one projection is at the upper or forward edge of one cam-surface the other projection is at the lowest part of the other cam-surface, the object being to cause a tilting movement of the seat in the act of shifting it 100 forward or backward for the purpose of rais-

ing the forward edge thereof. This construction is very similar to that set out in my other application, hereinbefore referred to. The upper portions of the plates F are provided with end guides, F', to retain the seat H in proper adjustment, to prevent binding against the frame C. These plates F are also provided with a rack, I, with the teeth of which a pinion-segment, M, works. The segment M is formed upon the radial arms L of the seat-back, which arms are pivoted at l to the plate C and work through the opening or notch n between the flanges N, which flanges project from the plate C and close the open space that would otherwise be formed between the seat H and plate C or frame A, thereby preventing anything falling from entering the working parts, and also preventing injury by inclosing the gearing. The ends of the slot or notch act, in a measure, as stops for the arm L, but the main strain is received by the striker-blocks S, secured to the arms B. By this construction it is seen that upon shifting the arm L the seat H will be shifted also, advancing toward what will be the front of the seat, and at the same time (through the agency of the cams) the forward edge will be raised and the rear edge lowered. The pinions M positively and uniformly move the seat at both ends simultaneously, and will also act as locks to hold it down into position; and these pinions are located equidistant between the cam-faces d, so that the rack I, while it oscillates, always moves uniformly over the pitch-circle of the pinion M. Pivoting the arm L to the plate C admits of the upper portion of the seat-arm B being left clear and unobstructed, greatly improving the appearance of the seat as an entirety.

J is the seat-back, which may be of any ordinary construction, but preferably with the head-rest j, and is pivoted by the hinge-connection K to the arms L. The construction of this hinge is clearly shown in Figs. 3 and 4. The hinge-plate O is secured in the usual manner upon the end of the seat-back, and is hinged at k by a fixed fulcrum to the arm L.

The plate K is provided with a rest, R, and two lugs, r, located therein. The arm L is provided with a projection, P, which is furnished with two oppositely-facing stops, p, and the projecting stop p', which works between the lugs or stops r, limiting the movements of the seat-back upon the arms L. Hinged within the rest R at q, and facing in opposite directions, are the two gravity-pawls Q, adapted to catch upon the faces p, but not both at the same time. These pawls are counterweighted, as at q', so that when the seat-back is thrown into position the upper pawl falls into locking position and prevents the upper edge of the seat-back being thrown forward, while one of the lugs r rests against the projection p' and prevents the seat-back being thrown backward. From this it is seen that when the seat-back is thrown from one side to the other it is

automatically locked, and yet at all times has a positive pivot-connection to the arm L, obviating any jarring or excessive wear. When the arm and seat-back are raised to a position vertical over the seat, the tendency of both pawls Q will be to fall away from the faces p; hence when the back is raised to this position it is unlatched, and may be tipped upon its arm L to the proper position before being lowered into place. It will also be observed that in shifting the seat-back it cannot be oscillated upon its supporting-arms L until after it has been raised to a substantially vertical position over the car-seat; hence the shifting is accomplished in the most easy and graceful manner. This will be appreciated when we consider that in the Cobb device, or that shown in Patent No. 281,129, hereinbefore referred to, if the lower edge of the back next to the aisle be caught, the seat-back will be unlatched from one arm, but not from the other; hence the most injurious torsional strain will result upon the connections and the transfer will be made in an awkward and unsatisfactory manner, and yet the Cobb locking device has been by far the best heretofore placed on the market. With my improved device such a premature unlatching is absolutely impossible, and the most careless and ignorant handling of the seat-back cannot result in undue wear or excessive strains, and all movements of the working parts are so gradual and uniform that the operation of the device causes no perceptible noise.

While I prefer the construction shown, the details thereof may be modified without departing from my invention. For instance, it will be readily understood that a delicate spring might be placed back of the pawls, so as to induce their action to lock the back without relying upon gravity, and yet which springs would be insufficient to prevent the pawls falling out of locking position in the transfer of the seat-back; or the pawls might be pivoted to the arm L instead of the casting O of the back. The employment of such a spring to act upon the pawls is indicated in Fig. 3.

Having now described my invention, what I claim as new, and desire to secure by Letters Patent, is—

1. In a seat, the combination of the main frame having cam faces or guides, a seat-supporting frame having racks and working upon said cam-faces to admit of reciprocation and to tilt the seat, the seat-back, and connecting-arms for hinging the seat-back to the frame, provided with gear-segments meshing with the rack on the seat-supporting frame, whereby the said gear-segment shifts the seat with a uniform movement and locks the frame against vertical displacement, substantially as and for the purpose specified.

2. In a seat, the combination of the main frame having cam faces or guides and exposed side arms, a seat-supporting frame having racks and working upon said cam-faces to ad-

mit of reciprocation and to tilt the seat, the seat-back, and connecting-arms pivoted to the main frame on a line with the seat for hinging the seat-back to the frame, and provided with 5 gear-segments meshing with the rack on the seat-supporting frame, whereby the said gear-segment shifts the seat with a uniform movement and locks the frame against vertical displacement, and a hinged locking-connection 10 between the pivoted arms and back, substantially as and for the purpose specified.

3. In a seat, the combination of the main frame having cam faces or guides, a seat-supporting frame having racks and working upon 15 said cam-faces to admit of reciprocation and to tilt the seat, the seat-back, connecting-arms for hinging the seat-back to the frame, provided with gear-segments meshing with the rack on the seat-supporting frame, whereby the said 20 gear-segment shifts the seat with a uniform movement and locks the frame against vertical displacement, a pivoted connection between said connecting-arms and back, and a gravity locking device independent of the pivoted connection 25 of said arms with the back to lock the seat-back thereto when in proper positions, substantially as and for the purpose specified.

4. In a seat, the combination of the main frame having cam faces or guides, a seat-supporting frame having racks and working upon 30 said cam-faces to admit of reciprocation and to tilt the seat, the seat-back, connecting-arms for hinging the seat-back to the frame, provided with gear-segments meshing with the 35 rack on the seat-supporting frame, whereby the said gear-segment shifts the seat with a uniform movement and locks the frame against vertical displacement, a pivoted connection between said connecting-arms and back, a 40 gravity locking device independent of the pivoted connection of said arms with the back to lock the seat-back thereto when in proper positions, and adapted to unlock only when the connecting-arms have been raised to a substantially 45 vertical position, and when the seat-back is over the seat, whereby extremely high backs may be used, substantially as and for the purpose specified.

5. In a seat, the combination of the main frame, the seat-back, connecting-arms hinged at one end to the main frame and at the other to the seat-back by a positive fixed hinge-joint, and a lock independent of the hinge to lock 50 said back to said arms in its two extreme tilted positions thereon, substantially as and for the purpose specified.

6. In a seat, the combination of the main frame, the seat-back, connecting-arms hinged at one end to the main frame close to the seat 55 and at the other to the seat-back by a positive fixed hinge-joint, and a lock independent of the hinge to lock said back to said arms in its two extreme tilted positions thereon, and stops on said main frame to limit the throw of said 60 arms, substantially as and for the purpose specified.

7. In a seat, the combination of the main frame, the seat-back, connecting-arms hinged at one end to the main frame and at the other to the seat-back, and independent gravity 70 locking pawls or plates adapted to lock and unlock the back with the arms automatically upon reversing the seat-back, substantially as and for the purpose specified.

8. In a seat, the combination of the main frame, the seat-back, connecting-arms hinged at one end to the main frame and at the other to the back, and a lock to lock the arms and back rigidly together during their upward movement in transferring the back, and automatically unlock these parts when substantially 8c above the seat, substantially as and for the purpose specified.

9. In a seat, the combination of the main frame, the seat-back, connecting-arms hinged 85 at one end to the main frame and at the other to the back, and a lock to lock the arms and back rigidly together during their upward movement in transferring the back, and automatically unlock these parts when substantially 90 above the seat, and remain unlocked until the back is tipped and lowered, substantially as and for the purpose specified.

10. The combination of the main frame A, plates C, secured thereto and having the cam-faces d, seat-carrying frame F, working upon 95 said cam-faces and having rack I, seat-back J, and arms L, pivoted at l to the main frame near the seat, hinged at their upper ends to the seat-back, and provided on their lower ends 100 with gear-segments M, adapted to mesh with rack I, substantially as and for the purpose specified.

11. The combination of the main frame A, plates C, secured thereto and having cam-faces d, seat-carrying frame F, working upon 105 said cam-faces and having rack I, seat-back J, arms L, pivoted at l to the main frame near the seat, hinged at their upper ends to the seat-back, and provided on their lower ends 110 with gear-segments M, adapted to mesh with rack I, seat H, and flanges N, extending from the plate C or main frame to close the space between the seat and frame, and between which flanges the arms L work, substantially 115 as and for the purpose specified.

12. The combination of the main frame A, plates C, secured thereto and having the cam-faces d, seat-carrying frame F, working upon 120 said cam-faces, provided with end guides, F', having rack I, seat-back J, removable seat H, and arms L, pivoted at l to the main frame near the seat, hinged at their upper ends to the seat-back, and provided on their lower ends with gear-segments M, adapted to mesh with rack 125 I, substantially as and for the purpose specified.

13. The combination of the main frame A, plates C, secured thereto and having the cam-faces d, seat-carrying frame F, working upon 130 said cam-faces, provided with end guides, F', and having rack I, seat-back J, removable seat

- H, arms L, pivoted at l to the main frame near the seat, hinged at their upper ends to the seat-back, and provided on their lower ends with gear-segments M, adapted to mesh with 35
5 rack I, and flange N, extending from the plate C or main frame to close the space between the seat and main frame, and between which flanges the arms L work, substantially as and for the purpose specified.
- 10 14. The combination of the seat-back and its hinge-plate O, having the stops r r, with the arm L, for hinging the said back to the seat-frame, having its upper end hinged to the plate O of the back and provided with a stop, 40
15 p', working between the stops r, to limit the throw of the seat-back upon its arm, and further provided with stops p p, facing in opposite directions, and two pawls, Q, carried between the plate O and arm L, to engage with 45
20 the stops p and securely lock the arm and back together, substantially as and for the purpose specified.
- 15 15. The combination of the seat-back and its hinge-plate O, having the stops r r, with the 45
25 arm L, for hinging the said back to the seat-frame, having its upper end hinged to the plate O of the back and provided with a stop, p', working between the stops r, to limit the throw 50
30 of the seat-back upon its arm, and further provided with stops p p, facing in opposite directions, and two weighted or gravity pawls, Q, carried by the plate O, and arranged between 55
- the plate O and arm L, and adapted to engage with the stops p and securely lock the arm and back together, substantially as and for the purpose specified. 35
16. In a seat, the combination of the main frame, the shifting seat and reversible back, pivoted connecting-arms to support the back and shift the seat, a pivot-connection between the said arms and back, and a gravity locking device independent of said pivot to lock the seat-back to its arms when in proper position, substantially as and for the purpose specified. 40
17. In a seat, the combination of the main frame, the shifting seat and reversible back, pivoted connecting-arms to support the back and shift the seat, a pivoted connection between the said arms and back, and a gravity locking device independent of said pivot to lock the seat-back to its arms when in proper position, and adapted to unlock only when the connecting-arms have been raised to a substantially vertical position, and when the seat-back is over the seat, whereby extremely high seat-backs may be used, substantially as and for the purpose specified. 45
50

In testimony of which invention I hereunto set my hand.
